(57) **CLAIM**

The ornamental design for a strap container, as shown and described.

DESCRIPTION

FIG. 1 is a front, right, and bottom perspective view of a strap container, showing my new design;

FIG. 2 is a front, right, and top perspective view thereof;

FIG. 3 is a front, left, and bottom perspective view thereof;

FIG. 4 is a front, left, and top perspective view thereof;

FIG. 5 is a front elevational view thereof;

FIG. 6 is a right elevational view thereof;

FIG. 7 is a left elevational view thereof;

FIG. 8 is a top plan view thereof;

FIG. 9 is a bottom plan view thereof;

FIG. 10 is a cross sectional view thereof, taken along the line 10-10 in FIG. 7;

FIG. 11 is a cross sectional view thereof, taken along the line 11-11 in FIG. 5;

FIG. 12 is a front elevational view of a strap container with an unclaimed shackle;

FIG. 13 is a right elevational view thereof;

FIG. 14 is a left elevational view thereof;

FIG. 15 is a top plan view thereof; and,

FIG. 16 is a bottom plan view thereof.

The broken lines in the drawings represent environmental structure only and form no part of the claimed design.

1 Claim, 5 Drawing Sheets
